Specification for Design.

Patented Dec. 13, 1921.

Application filed January 15, 1921. Serial No. 437,599. Term of patent 7 years.

To all whom it may concern:

Be it known that I, FRANK B. ASTON, a citizen of the United States, residing at Elgin, in the county of Kane and State of Illinois, have invented a new, original, and ornamental Design for Casket-Handles, of which the following is a specification, reference being had to the accompanying drawing, forming a part thereof.

The figure is a perspective view of a casket handle, showing my new design.

I claim:

The ornamental design for a casket handle, as shown.

FRANK B. ASTON.
